ALBERT H. STEBBINS, OF LOS ANGELES, CALIFORNIA.

CONCENTRATOR.

Application filed July 19, 1926. Serial No. 123,332.

This invention relates to circular concentrators.

Various attempts have been made heretofore to develop a satisfactory form of circular concentrator, but difficulty has been experienced in developing a satisfactory construction, due to the fact that in circular concentrator decks the progressive or oscillatory movement imparted to the deck is necessarily greater near the outer periphery of the deck than at its inner periphery. It therefore follows that if the materials being treated are permitted to move radially of the deck while traveling over the deck surface they are subjected to a progressive movement that increases in intensity as the materials approach the outer periphery of the deck and which decreases in intensity as the materials approach the inner periphery of the deck. In the circular deck constructions employed heretofore this variation in the strength of the progressive movement imparted to the materials upon different parts of the deck has made it difficult to secure the desired separation of the materials.

One of the important features of the present invention therefore resides in the construction of a circular deck whereby the materials being treated are caused to travel in channels which are arranged concentric or approximately concentric with the central axis of the deck, and as a result of this construction the materials traveling in a particular channel remain the same distance from the axis of the deck while traveling throughout the length of the channel. It therefore follows that the materials in a particular channel may travel entirely around the deck without being subjected to a change in the intensity of the progressive movement.

One of the principal advances of a circular concentrator over the usual table concentrator, resides in the fact that by causing the materials to travel in the path of a circle instead of in a straight line, a relatively long distance of travel for the materials may be obtained on a small machine, and this is particularly desirable when fine materials which do not separate rapidly are being treated.

Another feature of the present invention therefore resides in the construction whereby the materials being treated may be advanced upon the deck surface over a path that makes

more than one complete revolution upon the deck surface so that the material delivery ends of the channels extend around into overlapping relation with the material receiving ends of the channels.

Another feature of the invention resides in the construction of the material receiving channels whereby the concentrates that gradually work down in the channels under the tailings crowd the tailings out of the channels. A further feature resides in the construction whereby smooth gradually widening spaces are provided between the channels. These spaces are formed by decreasing the width and depth of the channels as they approach the concentrate wall, and the spaces help to effect the separation of the materials being treated, due to the tendency of the coarse particles crowded out of the channels to move laterally of the spaces more rapidly than the fine particles.

Still another feature of the invention resides in the construction of the operating means provided to impart a progressive oscillatory movement to the deck to advance the materials over its surface.

Other features of the invention and novel combination of parts in addition to the above will be hereinafter described in connection with the accompanying drawings which illustrate good practical forms of the invention.

In the drawings:—

Fig. 1 shows a circular concentrator constructed in accordance with the present invention, the supporting frame being shown in end view and the deck in vertical section;

Fig. 2 on an enlarged scale is a perspective view of the deck of Fig. 1;

Fig. 3 is a top plan view showing a modified type of deck mounted upon the supporting frame of Fig. 1;

Fig. 4 is a side elevation of the concentrator of Fig. 1;

Fig. 5 on an enlarged scale is a perspective sectional view of a modified deck construction;

Fig. 6 is a view similar to Fig. 5 but shows still a different form of deck construction, and

Fig. 7 is a fragmentary, transverse, sectional view of a portion of the deck, the view being taken near the discharge end of several of the channels.

The frame of the circular deck or table

2
may be constructed of an annular casting 10 having the central hub 11 which is connected to the outer portion of the casting by the spokes 12. Upon the annular casting 10 are mounted the upstanding outer wall 13 and the inner annular wall 14. These features, however, may be varied as desired.

The frame for supporting the deck or table for rotative movement may be variously constructed and as shown is formed of the side rails 15 that are secured to the uprights 16 and the sides of the frame are connected by the transversely extending braces 17.

15 The concentrator deck or table is supported by its frame for rotative movement in a horizontal plane, and this is accomplished in the construction shown by rigidly securing the hub 11 of the deck casting to 20 the upper end of a vertical shaft 18, and this shaft is journaled in the spaced bearing brackets 19 and 20, these brackets being mounted upon the centrally disposed rails 21 of the supporting frame. The 25 weight of the deck is preferably supported by the antifriction bearings 22 positioned between the upper end of the bearing bracket 20 and the under face of the hub 11.

As above stated an important feature of 30 the present invention resides in the construction of the deck surface and of the channels in which the materials travel while they are being separated, and the deck construction shown in Figs. 1 and 2 of the drawings will 35 now be described.

The deck surface 23 may be formed of sheet metal, wood or any other suitable material and is arranged to form a receptacle or bowl having the shape of a frustum of a 40 cone the inclined walls of which slope downwardly toward the central axis of the deck, the arrangement being such that the materials that escape from the material receiving channels will flow down the inclined deck 45 surface toward the inner annular wall 14 of the deck. The deck surface 23 may be supported in spaced relation to the annular casting 10, and at the desired inclination to said casting by the inclined bars 24 the outer 50 ends of which may be secured to the outer wall 13 of the deck and the inner ends of which may be secured to the inner wall 14.

The materials to be treated may be delivered to the deck surface by a hopper 25 55 preferably disposed near the outer periphery of the circular deck, and the rate at which the materials are delivered to the deck surface by the hopper will be controlled by a sliding gate 26. The deck surface 23 is 60 preferably constructed to form the material receiving channels 27 which are arranged concentric or substantially concentric with the central axis of the circular deck, as will be apparent from the drawings. If the material receiving channels 27 are made rela-

tively long so that the heavier materials or concentrates within a channel may have ample opportunity to settle, then a relatively thick layer of materials may be delivered upon the concentrator deck by the feed hopper 25. 70 It is desirable to prevent this relatively thick layer of materials from flowing transversely down the inclined deck surface at points near the feed hopper and this is accomplished in accordance with the present 75 invention by providing each channel 27 near the feed hopper with an upstanding wall or riffle 28 which is disposed at the inner curved edge of the channel, as best shown in Fig. 5. These riffles 28 may be formed of a narrow 80 strip of sheet metal that may be tacked, soldered, or otherwise secured to the upstanding wall 29 of a channel, and the riffles preferably decrease in height in the direction in which they extend away from the hopper 25, 85 so that they gradually disappear at points some distance from the feed hopper 25, as will be apparent from Figs. 2 and 3.

The material receiving channels 27 are preferably formed upon the deck surface 23 90 by giving the same the stepped construction best shown in Figs. 5 and 6, wherein it should be noted that each channel consists of an upstanding wall 29 and an inclined floor portion 30, and it will be seen that the 95 floor portion slopes downwardly as it extends outwardly away from the central axis of the circular deck. As a result of this construction each channel has the form of a trough adapted to receive the concentrates 100 C, as indicated in Fig. 5. The construction is such that as the materials travel along the channels 27 under the influence of the deck movement, the concentrates will gradually work down under the lighter materials or 105 tailings, and these tailings will escape inwardly over the riffles 28 as these riffles gradually decrease in height, and will also flow inwardly at various points along the 110 channels as they are crowded out of the channels by the concentrates. This tendency of the concentrates to crowd the tailings out of the channels may be increased by gradually decreasing the depth of the 115 channels in the direction in which they extend, so that these channels become more and more shallow as they approach the concentrate wall, to be described.

The hopper 25 preferably does not extend 120 entirely across the deck surface, but serves to deliver materials to be treated only to the channels 27 that are located near the outer wall 13 of the deck surface. As a result of this construction the tailings and any of the 125 concentrates that are crowded out of the outer channels 27 will enter other channels disposed near the inner wall 14 of the deck, for further treatment.

As the materials within a channel 27 reach the end of such channel they are directed 130

against a concentrate wall 31 having the buffer blocks 32 which give the wall the stepped construction shown, and the arrangement of this wall is such that it serves 5 to gradually direct the concentrates inwardly from the outer portion of the deck towards the inner wall 14. The concentrate wall 31, however, need not direct the concentrates entirely across the deck surface, 10 but may direct them into the channels 33 (see Fig. 2) along which the concentrates may travel until they reach one or more receptacles 34 adapted to receive the concentrates. The tailings that gradually work 15 downwardly towards the inner wall 14 of the circular deck as they are crowded out of the channels will pile up against the inner wall 14, along which they may travel under the progressive movement imparted to the deck 20 until they reach the discharge opening 35 through which they may pass into a tailing discharge hopper 36 that may be supported in the position indicated in dotted lines in Fig. 4.

25 The movement imparted to the circular deck to advance the materials along the channels 27 serves to throw the materials tangentially to the direction of movement, which is desirable as this tends to force 30 the concentrates against the upstanding wall 29 of each channel, thus causing the concentrates to accumulate at the outer or deep sides of the channels, while the tailings are crowded away from this portion of the channels 35 so that they flow inwardly over the inner edges of the channels towards the central axis of the deck.

In some cases it may be desirable to make 40 the channels 27 longer than those shown in Fig. 2 without at the same time increasing the diameter of the circular deck. This may be done in accordance with the present invention by constructing the channels 27 as shown in the modified construction of Fig. 45 3 wherein it will be seen that the materials being treated are directed around the concentrator deck through more than one complete revolution. This is accomplished by arranging the channels 27 so that the delivery end of some of the channels overlap the material receiving ends of other channels, as will be apparent from Fig. 3. The concentrate wall 31 shown in the modified construction of Fig. 3, it should be noted, extends spirally over the deck surface through 55 nearly a complete revolution and serves to direct the concentrates gradually inwardly from the outer portion of the deck surface to points near the inner wall 14 of the deck 60 where the concentrates escape through the discharge pipes 37. The tailings in the construction shown in Fig. 3 may escape through an opening in the inner wall 14 of the deck and fall into the hopper 36, as in 65 the construction of Fig. 1. The advantages secured through the use of a long deck reside not only in the fact that a better separation of the materials may be effected than can be secured when a short deck is used, but reside also in the fact that when a long 70 deck is employed the materials may be fed to the deck from the feed hopper in a much thicker layer than is practical when a short deck is employed. This is due to the fact that when a long deck is employed the thick 75 layer of materials has ample time to spread out and stratify before reaching the concentrate wall, while when a short deck is employed it is necessary to feed the materials to the deck in a relatively thin layer 80 in order to insure the desired separation of the materials before they complete their travel over the deck surface.

Various means might be provided for 85 rocking the deck about its supporting shaft 18 to impart a progressive movement to the materials being treated, but the nature of the movement imparted to the deck is important because, while it should be sufficiently energetic to insure travel of the materials in all 90 of the channels 27, the movement should not be energetic enough to disturb the stratification of the materials which gradually takes place over the deck surface. A good practical construction for imparting the desired 95 oscillatory movement to the circular deck is shown in the drawings and will now be described. The concentrator deck is provided with a cable receiving drum 38 which may be formed integral with the supporting casting 10 of the deck, and the drum 38 is adapted to receive the operating cable 39 which may be wrapped one or more times around the drum and is preferably secured thereto by a clamp 38a constructed to prevent the cable from slipping about the drum. The deck is rocked about its supporting shaft by pulling first one end of the cable 39 and then the other, and this is accomplished in accordance with the present invention by 105 connecting the ends of the cable 39 to the oppositely extending arms of a crank shaft 40, the ends of which shaft are rotatably mounted in bearing brackets 41 that are secured to the main frame. The crank shaft 40 is provided near one side of the supporting frame with the laterally extending arms 42 that are connected by the wrist pin 43 and this crank shaft is provided near the opposite side of its supporting frame with the laterally extending arms 44 which are connected by the wrist pin 45. One end portion 46 of the operating cable 39 is led over a grooved sheave 47 and then extends downwardly to the wrist pin 45 to which it is secured, and the opposite end portion 48 of the cable 39 is led over a grooved sheave 49 and extends downwardly from this sheave 49 to the wrist pin 43 to which the end of the cable is secured. The sheaves 47 and 49 are 110 115 120 125 130

rotatably supported by a transversely extending shaft 50 the ends of which are journaled in bearing brackets 51 secured to the supporting frame.

5 The crank arms just described extend in opposite directions, as clearly shown in Fig. 1, and it will therefore be seen that as the crank shaft 40 is rocked in one direction it will tension one operating cable and slack off the other to rotate the circular deck in one direction, and as the crank shaft 40 is rocked in the opposite direction it will actuate the cable 39 to pull the circular deck in the opposite direction. In order to impart a 10 progressive movement to the materials upon the deck surface it is necessary to move the deck more energetically in one direction than in the other. This is accomplished in an extremely satisfactory manner by the 15 operating mechanism just described since as the crank shaft 40 is moved to the position in which the crank arms lie in a vertical plane as shown in Fig. 4, the speed at which one cable is let off and the other is taken up decreases as the crank arms approach this 20 position, and as the crank arms are moved to an angle to the position in which they are shown in Fig. 4, the speed at which one cable is taken up and the other is let off will increase as the crank arms approach a horizontal 25 position. In other words, the angular movement of the crank arms is utilized to impart a variable speed movement to the opposite ends of the deck operating cable. It 30 will be noted that the idle sheave 49 upon the shaft 50 is larger in diameter than the idle sheave 47. This is desirable because it lifts one coil of the cable about the drum 38 above the other, so that they will not interfere with each other and also because this 35 construction helps to maintain a uniform tension on the opposite ends of the cable 39 as the crank shaft is rocked back and forth.

40 45 The desired progressive movement may be imparted to the materials upon the deck surface by rocking the deck through a small angle, and it is therefore necessary to rotate the crank shaft 40 through only a small 50 part of a complete revolution, say through an angle of not more than 20° or 25°. Various means might be provided for imparting this rocking movement to the crank shaft 40 and in accordance with the present invention this is accomplished by providing an 55 operating cable 52 one end of which is secured to the upper wrist pin 45 of the crank shaft 40 and the other end of this cable is anchored to the supporting frame by an adjustable bolt 53. An intermediate portion 60 of the cable 52 is looped about a grooved sheave 54 that is mounted upon an eccentric 65 55. A second operating cable 56 has one end secured to the lower wrist pin 43 of the crank shaft and the other end of this cable

is anchored to the supporting frame by an adjustable bolt 57, while an intermediate portion of the cable 56 is looped about a grooved sheave 58 which is mounted upon the operating eccentric 59. The operating 70 eccentrics 55 and 59 are mounted upon and are rigidly secured to the power operated shaft 60 the ends of which shaft are journaled in the bearing blocks 61 mounted upon the supporting frame. The eccentrics 55 and 59 are preferably spaced at an angle of 180° 75 to each other and as the power shaft 60 is rotated these eccentrics rotate within their respective sheaves and move the sheaves through orbital paths to thereby alternatively 80 tension and slack off the cables 52 and 56. This will serve to rock the crank shaft 40 back and forth between the positions in which it is shown in full lines and in dotted lines in Fig. 4. The speed at which the 85 circular deck is rotated will gradually decrease as the crank arms approach the full line position of Fig. 4 and the speed will gradually increase as the arms are moved to the inclined position indicated in dotted lines 90 in Fig. 4. This variable speed movement imparted to the deck will serve to advance the materials in the channels 27 from the feed hopper 25 towards the concentrate wall 31 in a very satisfactory manner. The power operated shaft 60 is preferably provided 95 with a fly wheel (not shown) to steady its rotative movement.

The separation of the materials upon the deck surface may be assisted by the use of 100 air that is forced upwardly through the deck surface and to this end air apertures may be formed within the deck surface throughout the length of each channel 27, or if desired the apertures may be formed in only that 105 portion of the channels which lie near the feed hopper; in any event, when air is employed to promote the separation of the materials the strength of the air should be strongest near the feed hopper and should 110 gradually decrease as the channels approach the concentrate wall. This may be accomplished by reducing the number and size of the apertures formed along the channels 27. In the modified construction shown in Fig. 115 5 the concentrator deck is formed of wood and the channels 27 are produced by cutting such channels in the upper face of the wooden deck 62. In the modified construction shown in Fig. 6 the deck construction differs 120 from that shown in Figs. 1 and 2 in that a separate air chamber is formed below each channel 27, these air chambers being produced by providing the vertical walls or partitions 63 below the deck surface and 125 which extend upwardly from the floor plate 64. This modified construction of Fig. 6 permits complete control of air passing upwardly through the apertures 65 in any channel and constitutes a stiff and durable 130

deck construction, but is more expensive to construct than that shown in Figs. 1 to 5 inclusive.

As above stated the material receiving channels 27 preferably grow more shallow as they approach the concentrate wall, as will be apparent from Fig. 7 where some of the channels 27 are shown as quite shallow and as having the smooth spaces 66 between them. These spaces 66 which gradually increase in width near the concentrate wall are not waste portions of the deck surface, but are useful because by the time the materials being treated approach the concentrate wall the fine tailings will have been crowded or forced out of the channels so that there will remain the fine and coarse values and the coarse tailings. As the coarse tailings and fine values are crowded out of the channels 27 onto the surfaces 66 the tailings will slide or roll quickly over these surfaces in the direction in which they slope, while the fine values will travel across these surfaces more slowly. In this manner the smooth surfaces 66 help to separate the fine values from the tailings and this particular separation is assisted by the direction of movement imparted to the materials by the deck.

30 What is claimed is:—

1. A circular concentrator deck, comprising in combination, a deck frame having a frusto-conical shaped deck surface the center of which is open and which surface slopes downwardly towards its central axis to direct the tailings down the inclination of the deck toward said central opening, material receiving channels formed upon the deck surface and constructed so that they 35 extend around the deck through more than one complete revolution upon a single deck surface and having their forward and rear ends disposed in overlapping relation upon a non-overlapping deck surface.

45 2. A circular concentrator deck, comprising in combination, a deck frame having an annular deck surface and provided with material receiving channels formed upon the deck surface and disposed so that they direct the concentrates entirely around the deck through one complete revolution and partly around the deck a second time while they remain in the same plane upon the deck surface, and means for oscillating the deck 50 to advance the materials along the channels.

55 3. A circular concentrator deck, comprising in combination, a deck frame having an annular deck surface and provided with a tailing discharge opening and with curved 60 riffles, a concentrate wall provided upon the deck surface to extend in a spiral manner over the deck surface and constructed to direct the concentrates progressively inwardly from the outer wall of the deck to positions near the inner periphery of the 65

annular deck surface and means for oscillating the deck to advance the materials around the deck.

4. A circular concentrator deck, comprising in combination, a deck frame having a frusto-conical shaped deck surface that slopes downwardly toward its central axes, riffles for directing the materials around the deck surface and arranged to arrest the flow of the materials toward the center of the deck, a concentrate wall arranged to extend in a spiral manner from the outer periphery of the deck inwardly to direct the concentrates inwardly toward the center of the deck, and means for oscillating the deck to 70 advance the materials over the deck surface.

5. A circular concentrator deck, comprising in combination, a deck frame having an annular deck surface, material receiving channels formed upon the deck surface and constructed so that they extend around the deck through more than one complete revolution and are arranged with their material receiving ends disposed near the outer periphery of the deck while their delivery ends 80 lie near the inner periphery of the deck and in overlapping relation to the material receiving ends.

6. A circular concentrator deck, comprising in combination, a deck frame having a frusto-conical shaped deck surface that slopes downwardly toward its central axis and which is provided with a stepped construction in cross section to form material receiving channels, and each channel having 85 an inclined floor that slopes downwardly in a direction to direct the materials outwardly away from the center of the deck, and means for oscillating the deck to advance the materials along the channels.

7. A circular concentrator deck, comprising in combination, a deck frame having an annular deck surface, material receiving channels formed upon the deck surface and constructed so that they extend around the deck through more than one complete revolution and are arranged with their material receiving ends disposed near the outer periphery of the deck while their delivery ends lie 90 near the inner periphery of the deck and in overlapping relation to the material receiving ends, and a concentrate wall extending over the deck surface between the overlapping portions of the channels.

8. A circular concentrator deck, comprising in combination, a deck surface that is provided with material receiving channels extending about the deck surface approximately concentric with the central axis of the deck, each channel being formed with an upstanding wall portion and a floor portion that slopes downwardly away from the central axis of the deck to the wall portion and adapted to direct the heavier materials outwardly into the deepest portion of the chan- 100 105 110 115 120 125 130

- nel where they work downwardly under the lighter particles, and means for oscillating the deck to advance the materials along the channels.
9. A circular concentrator deck, comprising in combination, a frusto-conical shaped deck surface that is provided with material receiving channels extending in a curved path about the deck surface, said channels being formed with inclined floors that slope from the inner side of a channel in a downward direction away from the central axis of the deck toward the outer side of the channel to produce channels that gradually increase in depth from their inner to their outer sides.
10. A circular concentrator deck, comprising in combination, a deck frame hav-

ing an annular deck surface provided with a central opening and the surface being supported so that it slopes downwardly in a direction to direct the materials toward the central opening, material receiving channels formed upon the deck surface and constructed to retard the flow of the concentrates toward said central opening, means for imparting a progressive rocking movement to the deck frame, and a retaining wall provided at the inner periphery of the deck surface and adapted to confine the tailings for further treatment as they travel around the deck surface against said wall.

In testimony whereof, I have signed my name to this specification.

ALBERT H. STEBBINS.
